(57) **CLAIM**

The ornamental design for a connector, as shown and described.

DESCRIPTION

FIG. 1 is a perspective view of the rear, top, and left side view of a first embodiment of the connector;

FIG. 2 is a perspective view of the front, bottom, and left side view of the first embodiment of the connector;

FIG. 3 is a top view of the first embodiment of the connector;

FIG. 4 is a bottom view of the first embodiment of the connector;

FIG. 5 is a rear view of the first embodiment of the connector;

FIG. 6 is a front view of the first embodiment of the connector;

FIG. 7 is a right side view of the first embodiment of the connector;

FIG. 8 is a left side view of the first embodiment of the connector;

FIG. 9 is a perspective view of the rear, top, and left side view of a second embodiment of the connector;

FIG. 10 is a perspective view of the front, bottom, and left side view of the second embodiment of the connector;

FIG. 11 is a top view of the second embodiment of the connector;

FIG. 12 is a bottom view of the second embodiment of the connector;

FIG. 13 is a rear view of the second embodiment of the connector;

FIG. 14 is a front view of the second embodiment of the connector;

FIG. 15 is a right side view of the second embodiment of the connector; and,

FIG. 16 is a left side view of the second embodiment of the connector.

The dash-dash broken lines in the drawings show portions of the connector that form no part of the claimed design. The dot-dash broken lines in the drawings show boundaries of the claimed design and form no part thereof.

1 Claim, 6 Drawing Sheets
